US00D751547S

(12) **United States Design Patent**
Song et al.

(10) **Patent No.:** US D751,547 S
(45) **Date of Patent:** ** Mar. 15, 2016

(54) **TABLET PERSONAL COMPUTER**

(71) Applicants: **Hisense Co., Ltd.**, Qingdao, Shandong (CN); **Hisense USA Corporation**, Suwanee, GA (US)

(72) Inventors: **Chunyan Song**, Shandong (CN); **Lili Guo**, Shandong (CN); **Wen Jiang**, Shandong (CN)

(73) Assignees: **Hisense Co., Ltd.** (CN); **Hisense USA Corporation**, Suwanee, GA (US)

(**) Term: **14 Years**

(21) Appl. No.: **29/498,770**

(22) Filed: **Aug. 7, 2014**

(51) LOC (10) Cl. **14-02**

(52) U.S. Cl.

USPC **D14/341**

(58) **Field of Classification Search**

USPC ..... D14/341, 342, 343, 336, 138 AD, 138 G, D14/219, 240, 248, 250, 496, 474, 203.7; 455/556.1, 558; 361/679.09, 679.01, 361/679.56, 679.3

CPC G06F 1/16; H04M 2250/22

CLAIM

The ornamental design for a tablet personal computer, as shown.

DESCRIPTION

FIG. 1 is a rear elevational view of a tablet personal computer showing our new design;

FIG. 2 is a bottom plan view thereof;

FIG. 3 is a perspective view thereof;

FIG. 4 is a front elevational view thereof;

FIG. 5 is a right side view thereof;

FIG. 6 is a top plan view thereof; and,

FIG. 7 is a left side view thereof.

1 Claim, 7 Drawing Sheets
